DESIGN FOR A TEXTILE FABRIC

Edith Margaret Swanson, New York, N. Y.

Application June 28, 1938, Serial No. 78,111

Term of patent 3½ years

To all whom it may concern:

Be it known that I, Edith Margaret Swanson, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The design is characterized by a series of raised zig-zag chenille cords forming the appearance of a staggered broken diamond pattern.

I claim:

The ornamental design for a textile fabric, substantially as shown and described.

EDITH MARGARET SWANSON.
